UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

SHOE-SEWING MACHINE.

1,118,524.

Specification of Letters Patent. Patented Nov. 24, 1914.

Application filed April 1, 1910. Serial No. 552,907.

To all whom it may concern:

Be it known that I, HARRIE A. BALLARD, a citizen of the United States, and a resident of Boston, in the county of Suffolk and State of Massachusetts, have invented certain new and useful Improvements in Shoe-Sewing Machines, of which the following is a specification.

This invention relates to shoe sewing machines, and more especially to the type known as chain-stitch machines which are usually employed for turned work, or for attaching a welt. It is customary to employ a curved oscillatory needle and a waxed thread, and the machine herein illustrated is designed to employ a needle and thread of this type.

The present invention embodies mechanism of improved construction adapted to be used instead of certain mechanism contained in my co-pending application, Serial No. 493,208, filed April 30, 1909. In said application is illustrated a welt guide and an oscillatory carrier therefor, said carrier being so mounted as to move the welt guide in an arc about the axis of the needle, and of equal radius. In said application, the mechanism for actuating the welt guide carrier includes friction devices whereby the carrier is locked in operative position, retracted against the tension of a spring, and again locked in retracted position, the locking and retracting being effected solely by means of friction. Another part of said application includes a work rest, a spring advancing the work rest toward the work, and friction mechanism similar to that of the welt guide mechanism for locking the work rest in operative position. The present invention is similar in general respects to that of said co-pending application, but it differs in the following respects:—The oscillatory carrier in the present invention is positively retracted. The oscillatory carrier and the work-rest are locked in operative positions by separate friction devices under the control of a single spring. The carrier and work rest are unlocked by one and the same movement of a single lever. The same lever serves to unlock and retract the carrier whether the shaft is driven forward or backward.

The oscillatory carrier is actuated and locked according to the present invention in the following manner: A spring is pro-

vided for advancing the carrier toward the work; the friction locking device is operated to lock the carrier in operative position, and the lever by which the carrier is positively retracted is also arranged to unlock the locking device immediately prior to retraction of the carrier, and to hold the locking device in released position until the carrier is permitted to return to operative position.

Another feature of the present invention is a work-engaging member which may be attached to said oscillatory carrier when it is desired to use the machine for sewing turned work, or any work other than the sewing of a welt. The member which may be hereby substituted for the welt guide is actuated in the same manner as a welt guide, and is likewise adapted to engage the work near the needle and in the line of the needle and on the same side of the work as the needle. Said member includes a relatively rigid member and a pointed plunger mounted therein and provided with a spring or other cushioning device whereby it may be forced back into its supporting member. The purpose of a work-engaging member of this character is to engage the work and remain stationary during the operation of the stitch-forming mechanism for the purpose of holding the work in fixed relation with the frame of the machine, and to thereby insure uniformity of the stitches and consequently a fine grade of work. The engagement of this member is initially yielding, and then supplemented by further engagement which is likewise yielding, but which is under increased tension. The yielding engagement finally becomes positive, when the carrier for supporting the member is locked as previously stated.

The improvement in construction embodied in the present invention is illustrated upon the accompanying drawings, and described in the following specification.

On the drawings.—Figure 1 represents a left side elevation of the head of a chain-stitch shoe sewing machine of which a portion is broken out in order to expose interior mechanism. Fig. 2 represents a rear elevation of a portion of the mechanism for operating the oscillatory carrier and the work rest. Fig. 3 represents a horizontal section on line 3—3 of Fig. 2. Fig. 4 represents an elevation of one end of the

oscillatory carrier and one of its supporting arms. Fig. 5 represents a section on line 5—5 of Fig. 1. Fig. 6 represents a section on line 6—6 of Fig. 3. Fig. 7 represents a 5 section on line 7—7 of Fig. 1. Fig. 8 represents an elevation of a device adapted to be mounted on said oscillatory carrier for engaging the work. Fig. 9 represents a top 10 plan view thereof in which a portion is broken away to expose the interior. Figs. 10, 11, and 12 represent side elevations of various levers for operating the oscillatory carrier. Fig. 13 represents a section on line 13—13 of Fig. 6. Fig. 14 is a horizontal 15 section of the thread tension devices. Fig. 15 represents a vertical section showing spring tension mechanism for projecting the work rest toward the work.

The same reference characters indicate the 20 same parts wherever they occur.

Before describing the new features of the present invention, it will be necessary to describe in a general way the machine to which the present invention relates.

25 Referring first to Fig. 1,—15 represents the frame or head in which the several instrumentalities of a shoe-sewing machine are mounted. The head provides bearings for a prime power shaft 16 which, when driven 30 forward, revolves in the direction indicated by the arrow and upon which are mounted the various cams for transmitting motion. 17 represents the needle which is of the hooked, oscillatory type, and which is 35 mounted to oscillate upon a stud 18. 19 represents a work-rest against which a shoe α may be held during the sewing operation. The work-rest is in the form of a bar and is mounted in guides 20, 20 in which it is 40 longitudinally movable. The rear of the work-rest is provided with a gear rack 21 which intermeshes with a pinion herein-after described, said pinion being subject to spring tension which normally tends to 45 project the work-rest toward the work. 22 represents a carrier which is mounted upon a pair of swinging arms 23, 24, said arms being pivotally mounted upon the head at 25 and 37. The radius of the arms 23 and 50 24 is equal to the radius of the needle 17 and the arms are connected to the carrier in parallel relation with each other, whereby they are adapted to carry the carrier bodily through an arc whose radius is equal to 55 the radius of the needle.

The work-engaging member forming a part of the present invention is shown by Figs. 1, 8, and 9, and comprises a socket member 27 adapted to be adjustably secured 60 to the forward end of the carrier 22. For the purpose of receiving the member 27, the end of the carrier is provided with a pivot stud 28 and a concentric slot 29. A clamping screw 30 inserted through said 65 slot and screwed into the socket member 27

is adapted to clamp the socket member to the end of the carrier. The mounting for the member 27 is such that its work-engaging portion may be set to engage the work in the line of the stitches. 31 represents a 70 socket or chamber formed in the member 27, said socket extending longitudinally thereof, and being larger at the rear end than at the forward end. 32 represents a plunger having a head 33. The plunger is 75 inserted in the socket so that the small end may project beyond the extremity of the socket member and so that the head occupies the larger part of the socket. A spring 34 compressed between the head 33 and the 80 screw plug 35 exerts its tension to project the plunger toward the work so that the point thereof may engage the same. The plunger and the member 27 are so constructed and arranged as to cause the work 85 engaging point to occupy a position as far from the axis of the stud 18 as the point of the needle. The point of the member is therefore adapted to move in an arc not only of the same radius as the needle, but 90 concentric therewith. A spring 36 is connected to some part of the carrier 22, such as the pivot 26, so as to exert its tension to move the carrier toward the work. The tension of the spring is applied continuously 95 and the carrier may be retracted against the tension of the spring by means hereinafter described. The forward end of the member 27 is preferably beveled, as clearly shown by Figs. 8 and 9, whereby it is given a blunt 100 chisel-like end. This end is adapted to engage the pulled-over portion of the upper as shown by Fig. 8, and press the upper snugly into the angle formed by the feather and shoulder of an insole, Fig. 8 showing 105 the upper thus pressed into the angle. The thrust of the member 27 is sustained by the channel guide 105 hereinafter described. The spring 34 by which the plunger 32 is projected permits the pointed plunger to 110 yield relatively to the member 27, and this yielding of the plunger is wholly independent of yielding pressure by which the member 27 is brought to bear against the upper. This permits the use of a relatively heavy 115 spring for forcing the member 27 against the upper, and the use of a relatively light spring for projecting the plunger 32. The plunger is arranged to engage the upper in the aforesaid angle, the shoulder of the insole bracing the upturned edge of the upper so that the pointed plunger may have the desired piercing effect.

37 represents a rock-shaft which forms the pivot of the rear arm 24. The arm is 125 pinned or otherwise affixed to the rock-shaft so that the oscillation of the shaft may be imparted to the carrier. The rock-shaft is mounted in bearings 38, as shown by Figs. 2 and 3, and is provided with a drum 39 130

and sleeve 40 arranged between the two bearings. The drum is pinned or otherwise affixed to the rock-shaft but the sleeve is loosely mounted thereon. The drum is formed as shown by Figs. 1 and 6, and is provided with an arm 41 which carries a roll 42. The roll is adapted to be engaged by a lever, hereinafter described, whereby the drum and rock-shaft may be positively oscillated against the tension of the spring 36. In this way, the carrier 22 is positively retracted.

One end of the sleeve 40 is formed with a pinion 43 which intermeshes with the rack 21 on the work-rest 19. The other end of the sleeve is formed with a flange 44 and the middle portion of the sleeve is formed with a drum 45 similar to the drum 39. The space between the flange 44 and drum 45 is occupied by a coil spring 46 by which tension is exerted upon the sleeve for projecting the work-rest toward the work.

The adjacent faces of the drums 39 and 45 are formed with concentric grooves 47 and 48 and said grooves are occupied by similar split rings 49 and 50 (see Fig. 6). The ends of the split rings are slightly separated and the space between them is occupied by studs 51, 52 of square formation, said studs being formed respectively upon levers 53 and 54. The levers 53 and 54 are subjected to spring tension which tends to turn them about the centers of the studs 51 and 52, and to thereby release the rings 49 and 50 so that they may in turn release the annular outer walls of the grooves 47 and 48. The locking levers 53 and 54 become locked with the drums through the medium of the friction rings as hereinafter explained. The free ends of the levers are formed with concentric slots 55 which are occupied by a pin 56 projecting from the head 15. The pin 56 limits the releasing movement of the levers 53 and 54 and serves to prevent turning of the drums when the rings are expanded against the drums. In the present embodiment of the invention, one spring 57 serves to release both of the levers 53 and 54, and the arrangement therefor is shown by Fig. 13; in which 58 represents a ring or yoke connected to one end of the spring and having ends projecting respectively into apertures formed in the two levers. The inserted ends of the ring 58 are loose in the apertures and are therefore adapted to permit slight movement of one lever relatively to the other, meanwhile applying tension to both.

The means for locking the friction devices includes a lever which is adapted to move the locking levers 53 and 54 against the tension of the spring 57. Said lever is shown by Figs. 1, 5, and 12 and is represented by the numeral 59. This lever is loosely mounted upon a stud shaft 60 which is affixed in

bearings 61 in the head 15, (see Fig. 2). The free end of the lever 59 is formed with a slot 62 which is concentric to the pivot 60.

Referring now to Fig. 5, 63 represents a stud which is cylindrical at one end, and which is screw threaded at the other. The intermediate portion 64 of the stud is square and is adapted to fit in the slot 62, and to be prevented from turning therein. A flange 65 is formed on the stud between the square portion 64 and the cylindrical end, and by means of said flange and a nut 66 arranged upon the screw threaded end, the stud may be clamped at any desired position in the end of the lever 59. The cylindrical end of the stud carries a sleeve 67 which is loosely mounted thereon. The sleeve is tapered from the ends toward the middle, thus providing opposed frusto-conical portions 68 and 69. The two conical portions of the sleeve are adapted to engage the locking levers 53 and 54 respectively, and for this reason, the outer edges of said levers are beveled, as indicated at 70 and 71 in Figs. 6 and 13. The sleeve is free to revolve and to slide longitudinally upon its supporting stud, and it is thereby adapted to engage the two levers 53 and 54 with equal pressure, and at the same time to move endwise in one direction or the other in order to accommodate itself to unequal positions of the locking levers. It is therefore assured that the sleeve may expand the locking rings with equal force against their respective drums.

The lever 59 is provided with a shoulder 72 which is adapted to be engaged by the face 73 of a cam lever 74. Said lever is loosely mounted upon the stud shaft 60 and has an arm 75 at the free end of which is a cam roll 76 which occupies the groove 77 in a cam disk 78 affixed upon the shaft 16. The levers 59 and 74 are provided with pins 79 to which are connected the opposite ends of a helical spring 80. The force of the spring 80 tends to move the sleeve 67 into engagement with the locking levers 53 and 54, and the force is greater than that of the spring 57. The spring 80, therefore, effects the expansion of the locking rings notwithstanding the opposing tension of the spring 57, when it is not positively prevented from doing so. The cam groove 77, however, is so formed as to move the face 73 to and from the shoulder 72, and by means of said face and the cam lever, the sleeve 67 is moved out of engagement with the locking levers 53 and 54, thereby permitting application of the tension of the spring 57 for unlocking the friction drums. Although the present drawings do not illustrate in detail any means for feeding the work, it may be assumed that the work is fed step-by-step in the usual manner. The purpose of providing the cam 77 and the levers for unlock-

ing the friction drums is to release the work-rest and the carrier 22 prior to the feeding movement of the work. The lever 59 not only effects the locking and controls the unlocking described, but it positively retracts the carrier while the same is unlocked. The retracting movement is imparted to the drum 39 by a plate 81 affixed upon the lever 59, as shown by Figs. 1 and 7. The plate is 5 adapted to engage the roll 42 mounted upon the arm 41 of the drum 39, and to oscillate the drum and thereby oscillate the rock-shaft 37, and so retract the carrier. The carrier is thus retracted and held in retracted 10 position so long as the plate 81 is held against the roll 42. When the plate is again moved to the rear to release the roll 42, the carrier is moved forward by its spring 36. The plunger 32 immediately engages the 15 work and the drum 39 is again locked by its friction devices under the control of the lever 59.

The operations thus far described occur when the shaft 16 is driven in the direction 20 of the arrow, that is, when the machine is operated for sewing. It is desirable to release the work-rest 19 and to retract the carrier 22 at the conclusion of a sewing operation in order to facilitate the removal of the 25 work. It is also desirable at this time to release the thread which is used in sewing, and to retract the needle from the work so that there will be no obstacle in the way of removing the work prior to severing the 30 thread. These desirable features are all herein embodied, but not in the same manner as they are carried out by the machine forming the subject matter of said copending application. For the purpose of describing the 35 manner in which the tension upon the thread is released, it will be necessary to first rehearse the description of the thread tension mechanism.

Figs. 1 and 5 show a roll 82 which engages 40 the thread between the supply and the needle. The thread which is indicated at 45 83 in Fig. 1, may be given a few turns around the roll 82, and then led through various guiding devices which conduct it to 50 a looper 84. The convolutions of thread about the roll 82 serve to rotate the roll when the thread is drawn toward the needle and the roll is subjected to suitable tension for resisting rotation whereby the desired 55 degree of tension may be imposed upon a the thread. The roll is loosely mounted upon a rod 85, of which one end is affixed in a bracket 86, and of which the other end is screw threaded and provided with a nut 87. 60 The thread roll is mounted between the bracket and the nut, and is subjected to the tension of a spring 88. A plate 89 is loosely mounted upon the rod and is interposed between the spring and the hub 90 of the 65 thread roll. A friction disk 91 is placed

upon the rod between the other end of the thread roll and the bracket 86, and the thread roll is thus clamped between the friction disk and the plate 89 when the tension of the spring 88 is applied to the hub 90. The plate 89 is provided with a hub upon which are formed crown teeth 92 which are adapted to coöperate with similar teeth 93 formed upon the rod 85. The teeth are so formed that a slight oscillation of the plate relatively to the rod causes the coöperative teeth to impart endwise movement to the plate and thus remove the tension of the spring 88 from the thread roll. For the purpose of oscillating the plate to thus relieve the thread roll, the plate is formed with a notch 94 which is occupied by a pin 95 carried by an arm 96 of a lever 97. The lever 97 is loosely mounted upon the stud shaft 60 and carries at its free end a pawl 98 which is adapted to coöperate with a tooth or shoulder 99 formed upon the hub of the cam disk 78. A spring 100 is connected to the pawl so as to hold the free end of the pawl against the periphery of said hub, and to also move the lever 97 in one direction. 101 represents a nose formed upon the lever 97 for the purpose of engaging a portion of the head 15 and thus limiting movement of the lever due to the tension of the spring 100. The shoulder 99 is so formed as to have no effect upon the lever 97 when the shaft 16 is driven forward in the direction of the arrow, but it is adapted to be actuated when the shaft is reversed, as hereinafter explained.

The arm 96 is formed with a face 102 which is adapted to engage a face 104 of the lever 59 with the same effect as that produced by the face 73 in engaging the shoulder 72 of the arm 59.

The releasing of the work-rest 19, the unlocking and retracting of the carrier 22, and the releasing of the thread roll 82 are effected at the completion of a sewing operation in the following manner:—The shaft 110 16, which is presumably provided with a hand wheel not shown, may be given a slight rotation in the reverse direction by means of the hand wheel. The degree of reverse rotation required is such as to cause the shoulder 99 to engage the pawl 98 and move the pawl into engagement with a fixed stop 103. The pawl in being thus retracted oscillates the lever 97 in the direction indicated by the arrow in Fig. 1. The results obtained by manually reversing the driving shaft are the releasing of the thread tension, the unlocking of the work-rest, the unlocking of the oscillatory carrier, and the positive retraction of the carrier. The needle actuating mechanism not shown is so related to the herein described parts of the machine as to be retracted to the position shown by Fig. 1 when the shaft is reversed. The work is therefore entirely freed and 115 120 125 130 135 140 145 150 155 160 165 170 175 180

may be readily removed from operative position before severing the thread.

In conclusion, it may be stated that the channel guide which is indicated at 105, is laterally movable and constitutes one element of the work-feeding means. The channel guide is also movable to a limited degree about the stud 18 upon which it is mounted, and it is the channel guide which supports the work against the pressure of the work-engaging members 27 and 32 mounted upon the oscillatory carrier 22.

Having thus explained the nature of my invention and described a way of constructing and using the same, although without attempting to set forth all of the forms in which it may be made or all of the modes of its use, what I claim is:

1. A shoe sewing machine comprising a stitch forming mechanism, a power shaft, an oscillatory carrier having a parallel motion for supporting a tool such as a welt guide or back gage, a thread tension, and means actuated by said power shaft when driven forwardly for locking, releasing and positively retracting said carrier, and when said power shaft is reversed, for releasing and positively retracting said carrier and for releasing said tension.

2. A shoe sewing machine comprising a stitch forming mechanism, a power shaft, an oscillatory carrier having a parallel motion for supporting a tool such as a welt guide or back gage, means for frictionally locking said carrier, a reciprocatory member for operating and releasing said locking means and for positively retracting said carrier, means actuated by said shaft when rotated forwardly for actuating said reciprocatory member, a thread tension, and means actuated by said shaft when rotated reversely for actuating said reciprocatory member and for releasing said thread tension.

3. A shoe sewing machine comprising a stitch forming mechanism, a work engaging member, an oscillatory carrier therefor having a parallel motion, friction mechanism for locking said carrier, yielding means for holding said locking mechanism inoperative, a reciprocatory driven member for operating and releasing said locking mechanism, and means adapted to be moved by said driven member to retract said carrier and work-engaging member.

4. A shoe sewing machine comprising a stitch forming mechanism, a reciprocatory carrier, a work-engaging member mounted on said carrier so as to engage the inseam of the work, means for locking the carrier so as to hold said work-engaging member against the work during operation of the stitch forming mechanism, means for retracting said carrier, and a spring tension member carried by and movable relatively

to said work-engaging member, said spring tension member having a point adapted to prick the work to prevent movement thereof.

5. In a shoe sewing machine, stitch forming mechanism and operating means therefor, two work-engaging members movable independent of each other, means for moving said members against the work with yielding tension, friction locking means for each of said work-engaging members, said locking means having operating members movable independently of each other, a reciprocatory driven member for moving both of said operating members at once to operate both locking means, and means interposed between said driven member and said operating members for transmitting operating movement and for equalizing the force by it transmitted to said operating members.

6. A shoe sewing machine comprising a stitch-forming mechanism including a curved oscillatory needle, an upper-engaging member for pressing the upper into the angle formed by the feather and shoulder of an insole, a carrier for said member whereby the work-engaging portion of said member is caused to traverse an arc concentric to the axis of said needle, a spring for forcing said carrier toward the shoe, a member for engaging the insole in the channel to brace the shoe against the forward thrust of said upper-engaging member, said upper-engaging member having a socket whose mouth is at the upper-engaging end thereof, a plunger movably arranged in said socket and having a pointed end for piercing the upper, and a spring for forcing said plunger toward the shoe.

7. In a shoe-sewing machine, a work-engaging member arranged to bear against the outer side of the stitch-receiving flange of the upper, means arranged to move said member to and from the work, and a supplemental work-engaging member carried by the first-mentioned member and arranged to tuck the upper into the angle formed by the shoulder and feather of the insole, said supplemental member being arranged to yield relatively to the first-mentioned member.

8. In a shoe sewing machine, a work-engaging member having a beveled end arranged to press the upper into the angle formed by the feather and shoulder of an insole, said member having a sharp-pointed spur arranged to pierce the upper in said angle to steady the shoe.

9. In a shoe sewing machine, a work-engaging member having a beveled end for pressing the upper into the angle formed by the feather and shoulder of an insole, said member having a socket the mouth of which is at said beveled end, a plunger movably arranged in said socket and having a pointed end protruding therefrom for pierc-

ing the upper to steady the shoe, and a spring for pressing said plunger against the shoe.

10. In a shoe sewing machine, a work-engaging member having a beveled end for pressing the upper into the angle formed by the feather and shoulder of an insole, means for carrying said member toward and from the work, said member having a socket 10 whose mouth is at said beveled end, a plunger movably arranged in said socket and having a pointed end protruding therefrom for engaging the upper in said angle, and a spring for pressing said plunger toward the 15 shoe.

11. In a shoe sewing machine, a work-engaging member having a beveled end for pressing the upper into the angle formed by the feather and shoulder of an insole, a carrier for said member, a spring for causing 20 said carrier to press said member against the shoe with yielding force, said member having a socket whose mouth is at said bevel-

eled end, a plunger movably arranged in said socket and having a pointed end for 25 engaging the upper in said angle, and a spring for projecting said plunger toward the shoe.

12. In a shoe-sewing machine, a work-engaging member arranged to tuck the upper into the angle formed by the shoulder and feather of the insole, means arranged to move said member to and from the work, and a supplemental work-engaging member carried by the first-mentioned member and 30 arranged to tuck the upper into said angle, said supplemental member being arranged to yield relatively to the first-mentioned member.

In testimony whereof I have affixed my 40 signature, in presence of two witnesses.

HARRIE A. BALLARD.
